UNITED STATES PATENT OFFICE.

KENNETH E. STUART, OF PHILADELPHIA, PENNSYLVANIA.

RAILWAY SELECTIVE SYSTEM.

1,243,457.

Specification of Letters Patent. Patented Oct. 16, 1917.

Application filed March 12, 1917. Serial No. 154,077.

To all whom it may concern:

Be it known that I, KENNETH E. STUART, a citizen of the United States, residing in the city of Philadelphia, county of Philadelphia, and State of Pennsylvania, have invented new and useful Improvements in Railway Selective Systems, of which the following is a specification.

My invention relates to a system whereby 10 a moving vehicle, such as a railway car or train, may select and control any translating device, as for example, a signaling or motive device for producing any desired effect at a station or stations of a series of 15 stations or other points along the path of travel of the vehicle.

My invention resides in such a system wherein the translating device is disposed either upon the moving vehicle or at any 20 other suitable point along its path of travel, or both, and in which contact conductors are disposed in the path of travel of the vehicle and so disposed as to their position with respect to each other and the path of 25 travel of the vehicle that contacts carried by the vehicle can coöperate with them to close the selected circuit or effect its desired operation.

My invention resides in the system and apparatus hereinafter described and claimed.

For an illustration of some of the forms my invention may take, reference is to be had to the accompanying drawings, in which:

35 Figure 1 is a plan view of a selector switch.

Fig. 2 is a cross sectional view through the switch shown in Fig. 1 with its cover and operating means.

40 Fig. 3 is a fragmentary side elevational view showing a contact shoe and a coöperating contact conductor.

Fig. 4 is a diagrammatic view illustrating an embodiment of my invention.

45 Fig. 5 is a fragmentary diagrammatic view illustrating a modification.

Fig. 6 is a diagrammatic view showing an application of my invention to a system of branched tracks.

50 Referring to Figs. 1 and 2, upon an insulating base *a*, carried by the metallic base

b, are the metallic stationary switch contacts 1, 2, 3 and 4 adapted to be engaged by the outer end of the metallic rotary contact brush *c* whose inner end *d* maintains electrical communication with the terminal binding post *e*. The member or brush *c* is supported at *f* upon the boss *g* carried by the rotatable member *h*, Fig. 2, disposed within the casing cover *i* and actuated by the shaft *j* carrying the hand wheel *k*. Secured to and rotatable with the shaft *j* is the wheel *m* having the notches *n*, corresponding in number with the fixed contacts 1, 2, 3, 4, and in which engages a roller *o* pivoted on the slidable member *p* thrust forward by the spring *q*. The roller *o* cooperates with the notched wheel *m* to hold the brush *c* in position to which moved for contact with the respective stationary contacts to prevent chance movement of the brush *c* from position to which moved. Upon rotating the hand wheel *k* the roller *o* will be thrown outwardly, due to the shape of the notch *n*, in opposition to spring *q*, and then ride over the edge of the wheel *m* and engage in the next notch or the notch corresponding to the selected position of the brush *c*. The stationary contacts 1, 2, 3, and 4 are supplied with the binding posts, 80 as indicated at *r*.

Referring now to Fig. 4, *V* represents a moving vehicle, such as a railroad car or train, having the wheels *s* traveling upon the track rails *t*, which latter are also indicated diagrammatically at the right of the figure. Upon the vehicle *V* are disposed two apparatus of the character described in connection with Figs. 1 and 2 with their respective contact brushes *c*, *c* connected by 85 conductor *u*.

By way of example, each of these switching apparatus has four stationary contacts, numbered as in Fig. 1, the contact brush *c* in the one case engaging contact 2 and in 95 the other the contact 3.

Carried by and insulated from the frame of the vehicle *V* are two sets of contact shoes, four in each set, the first set, *v*¹, *v*², *v*³ and *v*⁴ being connected respectively with 100 the contacts 1, 2, 3 and 4 of the left hand switching apparatus; and the other set com-

prises the contact shoes w^1 , w^2 , w^3 and w^4 connected respectively with the contacts 1, 2, 3 and 4 of the right hand switch.

These contact shoes are adapted to engage and make electrical contact with contact conductors disposed in the path of travel of the vehicle. These contact conductors may take the form of rails or other conductors extending suitable distances 10 longitudinally of the trackway. In Fig. 4 two of these contact conductors are indicated at x^2 and y^3 as of rail or T shape. In Fig. 3 is shown a fragment of the contact conductor x^2 in side elevation with its co-operating contact shoe v^2 making electrical contact therewith. The shoe v^2 is a conductor, as of iron or steel, supported upon the ends of the conducting springs z , z secured at z^1 to a member z^2 of wood or other 15 suitable insulating material upon the moving vehicle.

Returning to Fig. 4, the lateral positions of the other contact rails of the system located at different places along the railway 20 are indicated in dotted lines at x^1 , x^3 , and x^4 , y^1 , y^2 and y^4 .

G is a generator or other source of electric current with one terminal of which there is connected the contact conductor x^2 25 and with whose other terminal is connected one terminal of the electro-magnet or relay R whose other terminal connects with the contact conductor y^3 . The relay armature a^1 is adapted to engage and bridge the stationary contacts b^1 and c^1 , of which b^1 is connected to one terminal of the source G and c^1 connects with one terminal of each 30 of the translating devices L and M , either of which may be employed alone, and of which L is an incandescent electric lamp operating as an indicator or signal, and M is an electric motor, solenoid or other motive device, the other terminals of the translating devices L and M being connected to 35 the other terminal of the source G .

The track rails t , t are shown again in diagram to the right of Fig. 4, and disposed between them are the longitudinally extending contact conductors x^2 and y^3 above referred to. S is a track switch controlled or 40 operated by the motive device M for determining the direction of the vehicle which may be caused to leave the main track and pass over the branch track T .

50 The operation is as follows:

The vehicle or car V may be driven by any suitable power and may be, for example, a car of an automatic electric railway system driven by electric motors which are automatically controlled, without a motor-man upon the car.

Assuming the direction of travel to be that indicated by the arrow and that it is desired to set the track switch S so that the

vehicle shall pass over the branch track T 65 to the station A and to give an indication or signal thereat before arrival, the brushes c , c of the switching apparatus upon the car will be set to such positions that they will engage with those stationary contacts which are electrically connected with the contact shoes w^2 and w^3 which are so disposed with respect to each other transversely of the vehicle V that they will engage the contact conductors x^2 and y^3 when the vehicle reaches those conductors. We then have the switching mechanism in the position shown in Fig. 4.

Before the vehicle reaches the contact conductors x^2 and y^3 the circuit of the relay R 80 is open and therefore the armature a^1 will be resting against its stop d^1 , with the result that the circuits of the lamp L and motive device M are open.

Should the vehicle in moving in the direction indicated first at some point in its travel pass over other pairs of contact conductors differently positioned in the trackway, the circuits controlled by those contact conductors will not be closed because the contact brushes c , c are not in the proper position to effect that purpose.

However, upon reaching the conductors x^2 and y^3 a selective control is effected because the brushes c , c have previously been 95 put in engagement with those stationary contacts 2, 3 of the respective switches which are connected with those contact shoes, v^2 and w^3 , which are properly positioned to engage and contact with the contact conductors x^2 and y^3 . The circuit is therefore closed 100 through these contact conductors and the switching mechanism on the car, with the result that the relay R is energized and thereupon raises its armature a^1 and bridges the contacts b^1 and c^1 , thereby energizing the lamp L , which therefore gives a signal or indication of the approach of the vehicle V and in addition causes energization of the motive device M which will cause the track 105 switch S to move to such position that the car will be deflected to the branch track whose rails are t^1 , t^1 .

If either of the brushes c , c should occupy a different position than that indicated in Fig. 4, the circuit would not be closed upon traverse of the contact conductors x^2 and y^3 by the moving car, and therefore the switch S would not be thrown and the vehicle would proceed along the main track whose 110 rails are t , t .

From the foregoing it is seen that by properly positioning the switches upon the vehicle and by properly positioning the contact conductors in the trackway with respect to each other, there is effected a selection of 115 a circuit which is closed or controlled through the switching mechanism on the car.

Ordinarily vehicle switches with a few contacts in each will suffice to give a sufficient number of combinations. But if a greater number of combinations is required, 5 recourse may be had to many other analogous or similar arrangements, only one of which is indicated in Fig. 5.

In the latter case four switches with three contacts each are shown, by means of which 10 eighty-one different combinations are possible, wherefore eighty-one different circuits may be selected and controlled.

In this case it will be noted that four contact conductors are employed for each circuit 15 selected for control through them, and that altogether there are twelve different positions of the contact rails, as indicated. The circuit to be controlled has its terminals in the conductors 1_1 and 1_2 , connecting respectively 20 with the contact conductors f^2 , f^4 , f^7 and f^{12} , the positions of the other contact conductors at other places along the path of travel being indicated in dotted lines at f^1 , f^3 , f^5 , f^6 , f^8 , f^9 , f^{10} and f^{11} . With these 25 coöperate contact shoes g^1 to g^{12} , which in groups of 3 are connected to the respective stationary contacts of the switches upon the vehicle. It will be noted that the contact rails f^4 and f^7 , which coöperate respectively 30 with the second and third switches, are interconnected by the conductor h^1 , while the movable contact brushes c , c of the first pair of switches are connected to each other by the conductor h^2 , and the movable contact 35 brushes c , c of the other pair of switches are connected by the conductor h^3 . It will be noted, therefore, that the circuit whose terminals are 1_1 and 1_2 is closed through the contact conductors and the switches in series. 40 The mode of operation is the same as that described in connection with Fig. 4, the circuit whose terminals are 1_1 and 1_2 , containing a source of energy and any suitable translating device energized directly therefrom, or indirectly as by relay control as 45 described in Fig. 4.

Fig. 6 shows one of many possible applications of my invention to selective railway systems. It is here assumed that there are 50 only three contact shoes in each set in place of the four shown at v^1 , v^2 , v^3 , v^4 , and w^1 , w^2 , w^3 , w^4 , Fig. 4. There is therefore a like number in each set of stationary contacts, which may be sections of rails as already 55 described. These are shown in Fig. 6 as being outside the rails of the trackway. In practice they may be either within or without the track rails or part may be within and part without, but preferably they are within 60 the track rails as in Fig. 4.

MT represents a short section of the main track having branches B^1 , B^2 and B^3 . Branch B^1 is provided with sub-branches B_1^2 and B_1^3 , branch B^2 has sub-branches B_2^1

and B_2^2 , and branch B^3 has the sub-branches 65 B_3^1 and B_3^2 .

The respective switches for these branches are under the control of the respective sets of stationary contacts SB^3 , SB^2 , SB_1^3 , etc., in the manner previously described. These 70 sets are of two kinds—those which directly control branches and those which control sub-branches. The former may be designated master sets, since they must be capable of selectively operating their switches 75 for all vehicles which are destined for any of the sub-branches of their respective branches.

Considering the branch B^3 , for example, I provide the master set SB^3 in which there is 80 one contact rail on the left side and all three contact rails on the right side, the rail upon the left occupying position No. 3. Any vehicle in which the corresponding contact element No. 3 at the left is connected with any 85 one of the right hand group will coöperate with the master set SB^3 to close the switch for the branch B^3 . The vehicle will then be deflected to sub-branch B_3^1 or B_3^2 or will continue on the main branch B^3 according 90 to as the active right hand contact element is No. 1, No. 2, or No. 3. Stationary set SB_1^3 has but one rail upon the right—that in position No. 1. SB_2^3 has its right hand rail in position No. 2. The left hand rail in each 95 of the sets SB^3 , SB_1^3 , SB_2^3 is in position No. 3, this being the characteristic position for this series of switches.

A third sub-branch could be provided for branch B^3 if desired, there being one more 100 available combination with the No. 3 characteristic—that in which the right hand rail is in position No. 3. But in such case no cars would be left upon the main branch B^3 so that an extension of this branch would be 105 useless. But it is more desirable to dispense with the added sub-branch and its selective set, as shown in Fig. 6.

Branch track B^2 is similarly controlled by set SB^2 , the characteristic of the series of 110 sets of which this is the master set being position No. 2 at the left. Sub-branches B_2^1 and B_2^2 are under the control of SB_1^2 and SB_2^2 , respectively.

The remaining branch B^1 is shown without a master set of stationary contacts. This set is omitted for a reason similar to that already stated, viz: this being the last branch upon the system all cars intended for the other branches will have been selected 115 before this branch is reached, so that no further selection of a main branch is necessary. Or branch B^1 may be considered merely as an extension of the main track MT. 120

Vehicles which reach branch B^1 are switched to sub-branch B_1^2 if the active right and left contacts on the vehicle are

both in position No. 1 and to sub-branch B₂¹ if the active contacts are in position No. 1 at the left and No. 2 at the right, respectively. Those in which the connected contacts are in position No. 1 at the left and No. 3 at the right will proceed upon the branch B¹.

Similarly those vehicles in which the connected contacts occupy positions No. 2 at the left and No. 3 at the right will ultimately reach the end of main branch B².

This principle of operation may be applied to any desired number of main branches and sub-branches, each of the latter being many times branched if desired. A master selective set may be employed for each branch and another master set for each branched sub-branch.

While in the examples above described the translating devices are shown to be located along the path of travel of the vehicle, they may be located upon the car by connecting one or all of them in the conductor u or either or both of conductors h², h³ either in series with each other or in parallel with each other. And in such case the pairs of contact conductors in the track-way will be electrically connected with the source or generator G, and if desired other translating devices; or the contact conductors of a pair may be directly connected to each other and the source of energy G may also be upon the car connected in the conductor u or in either or both of conductors h², h³. Either of these latter examples will serve to indicate upon the car or cause a response of the car when the car reaches a certain place on its path of travel without necessity for watching for that particular point upon the path of travel.

Obviously also, in addition to the signals or translating devices as indicated in Fig. 4, additional translating devices may be located upon the car as in the conductor u so as to afford information thereon as to whether or not the desired control has been effected.

What I claim is:

1. In a railway selective system, the combination with a plurality of groups of contact elements disposed upon the vehicle, of stationary selective elements, one for each group of contact elements, disposed in proximity to the track, and so positioned with respect thereto that, as the vehicle passes, said stationary selective elements will contact with predetermined ones respectively of said groups of contact elements, a switch for each group, each switch having a plurality of contacts connected respectively to the contact elements of the respective group, a source of current, an electrically operated device, and means including circuit connections whereby a circuit may be completed

through said source, said electrically operated device and said switches when the stationary selective elements are in contact with the corresponding contact elements and the movable elements of the switches are set upon the corresponding contacts.

2. In a railway selective system, the combination with a plurality of contact elements carried by the vehicle, of means including a switch carried by said vehicle for electrically connecting certain desired ones of said contact elements, a source of electric current, an electro-responsive device, selective means located adjacent the track for engaging predetermined ones of said contact elements, and means electrically connecting said source, said electro-responsive device and said selective means, whereby, by a proper setting of said switch, the electro-responsive device will be energized when the selective means become operative.

3. In a selective system for moving vehicles, the combination with a vehicle and a track therefor, of a plurality of contact elements disposed upon one of them, and selective means carried by the other and adapted to engage certain predetermined ones of said contact elements as the vehicle passes, means including a plurality of circuit closing elements for electrically connecting certain desired one of said contact elements, a source of electric current, an electro-responsive device, means including said selective elements and connections therefor for electrically connecting, as the vehicle passes, the electro-responsive device, the source of current, the selective elements and the circuit closing elements, whereby said electro-responsive device will be operated only in case the circuit closing elements have been previously properly adjusted.

4. In a railway selective system, the combination with selective units located at intervals along the track, each unit consisting of a plurality of selective elements spaced apart and spaced from the track, the spacing being different for different units, of contact elements carried by the vehicle and spaced apart, said selective elements being so disposed that, as the vehicle passes the units, the selective elements will selectively engage those contact elements which are correspondingly disposed, means including a switch carried by the vehicle for electrically connecting certain desired ones of said contact elements, an electro-responsive device for each selective unit, energizing means for said electro-responsive devices, and means electrically connecting said electro-responsive devices with their respective selective elements, whereby the switch may be adjusted to cause selective operating of said electro-responsive devices.

5. In a railway selective system, the com-

- 5 bination with selective units located at intervals along the track, each unit consisting of a plurality of selective elements spaced apart and spaced from the track, the spacing being different for different units, of a plurality of groups of contact elements carried by the vehicle and spaced apart, said selective elements being so disposed that, as the vehicle passes any given unit, a contact 10 element of each group will be engaged by a selective element of that unit, a switch for each group of contact elements, each switch having a plurality of elements connected respectively to the contact elements of the corresponding group, connecting means including said switches for electrically connecting desired ones of said contact elements, an electro-responsive device for each selective unit, energizing means for said 15 electro-responsive devices, and means including said selective elements and connections therefor for electrically connecting, as the vehicle passes a given unit, the electro-responsive device and the selective elements 20 of that unit and the switches upon the vehicle, whereby the switches may be so adjusted as to cause selective operation of said electro-responsive devices.
6. In a railway selective system, the combination with a group of contact elements disposed upon the vehicle and spaced apart, of a group of stationary, spaced contact elements disposed in proximity to the track and spaced therefrom and so disposed that, 25 as the vehicle passes, contact will be effected between such of the moving contacts and such of the stationary contacts as are in alinement, an electro-responsive device, a source of current, a plurality of serially connected switches, means including said switches for electrically connecting desired ones of one group of contact elements, and means including certain of said contact elements and connections for electrically connecting, as the vehicle passes, said electro-responsive device, said source of current and said serially connected switches, whereby 30 said electro-responsive device will be operated only in case the switches have been previously adjusted to electrically connect such of said contact elements as are brought into contact with others as the vehicle passes.
7. In a railway selective system, the combination with a plurality of groups of selective contact elements, of means for connecting any desired contact element of one group with any contact element outside that group, said means including a switch contact for each element.
8. In a railway selective system, the combination with a plurality of groups of selective contact elements, of means for connecting any desired one of the contact elements of one group with any one of another group,

means for connecting any desired one of the 65 contact elements of a third group with any one of a remaining group, and means for completing a circuit through all of the contact elements thus connected.

9. A selective railway system comprising 70 a track having a plurality of branches at least one of which is branched, a switch for each branch, a set of selective elements for each switch, and a set of selective elements upon each vehicle, each vehicle set coöperating 75 with one or more of the switch sets to selectively operate the corresponding switches.

10. A selective railway system comprising 80 a main track, a branch from said main track and a branch from said branch track, a switch for each branch, selective elements beside the trackway controlling said switches, and selective elements upon each vehicle co-operating with one or more of the selective 85 elements beside the trackway to selectively operate the corresponding switches.

11. A selective railway system comprising 90 a track having a plurality of branches at least one of which is branched, a switch for each branch, a set of selective elements for each switch, a set of selective elements upon each vehicle, each vehicle set coöperating with one or more of the switch sets to selectively operate the corresponding switches, 95 and means for readjusting one of said co-operating sets to cause it to selectively operate different of said switches.

12. A selective railway system comprising 100 a main track, a branch from said main track and a branch from said branch track, a switch for each branch, selective elements beside the trackway controlling said switches, selective elements upon each vehicle co-operating 105 with one or more of the selective elements beside the trackway to selectively operate the corresponding switches, and means for readjusting said selective elements to vary the selectivity.

13. A selective railway system comprising 110 a main track, a branch from said main track and a branch from said branch track, a switch for each branch, sets of selective elements adjacent the trackway controlling said switches, and a set of selective elements 115 upon each vehicle coöperating with one or more of said first mentioned sets to selectively operate the corresponding switches to bring the vehicle upon a desired branch, each vehicle set coöperating with said first 120 mentioned sets to selectively operate all the switches between said main track and said desired branch.

14. In a railway selective system, the combination with a plurality of pairs of groups 125 of selective contact elements, of switching mechanism for each pair for connecting any desired element of one group of the pair

with any element of the other group of the pair, and means for completing a circuit through all of the elements thus connected.

15. In a railway selective system, the combination with railway vehicles, of a main track therefor, a main branch from said main track, branches from said branch track, a switch for each branch, sets of selective elements adjacent the trackway for controlling said switches, and selective elements upon each vehicle selectively coöoperating with the sets of selective elements control-

ling the switch for the main branch and that for any desired one of the branches of said main branch, whereby the selective elements controlling the switch for said main branch serve as a master set to cause the operation of the main branch switch by all vehicles destined for the branches of said main branch. 15

20 In testimony whereof I have hereunto affixed my signature this 10th day of March, 1917.

KENNETH E. STUART.
